RAIL FASTENING

Marvin L. Cantrell and Oscar A. Hed, Pueblo,
Colo., assignors to The Colorado Fuel and Iron
Corporation, Denver, Colo., a corporation of
Colorado

Application May 26, 1942, Serial No. 444,518

1 Claim. (Cl. 238—349)

This invention relates to rail fastenings of the type which employs a resilient lock for holding the rail against its seat with a spring action and is concerned more particularly with a novel fastening of this type in which the spring lock is held in its operative position on a tie plate by its action on a retaining member. The new fastening may be installed readily, requires little or no servicing, and may be made at low cost.

Rail fastenings have been devised heretofore in which a resilient rail lock is pivotally mounted in an opening in the tie plate and is held in position by a retaining member in the form of a spike disposed in the same opening in engagement with the outer face of the lock. In such fastenings, the spring lock normally exerts an outward thrust on the spike and is adapted to fulcrum on its pivotal mounting under the spring reaction so as to take up automatically any looseness which might otherwise develop between the parts due to wear, corrosion, etc. The proper functioning of this type of fastening, however, is dependent upon its correct installation and adequate maintenance. Unless the spikes adjacent the spring locks are driven carefully and uniformly the locks will normally exert different pressures on the rail, which is objectionable. Also, when the track is faulty, due, for example, to looseness of the ties on the bed, splitting or deterioration of the ties, or improper seating of the tie plates on the ties, there is a tendency for the spikes adjacent the locks to work out of the ties. This is so because each of the spikes is wedged in the plate by the spring lock with a greater thrust than the holding power of the tie, so that when the plate moves upwardly from the tie under the action of passing rail loads, the spikes tend to move with the plate out of the tie instead of the plate moving along the spike.

In another form of rail fastening, the spring lock is held in position by a retaining member which lies wholly above the bottom of the tie plate, a fastening of this type being shown in Boyce Patent No. 2,258,315. These fastenings, however, require a special form of aperture in the tie plate for receiving the spring lock. That is, the plate opening is undercut, and a lateral projection on the spring lock extends into the undercut portion so that the overhanging part of the plate prevents upward movement of the lock incident to the wave motion of the rail. The punching of undercut openings in the tie plate requires the use of special tools and increases appreciably the cost of the assembly.

Moreover, in fastenings of this type it is necessary to distort the lock by means of a special tool to permit insertion of the retaining member.

The present invention is directed to the provision of a novel rail fastening of the type including a spring lock held in position by a retainer, which does not require an undercut opening for the lock and may be installed without the use of a special tool for distorting the lock.

5 A rail fastening made in accordance with the invention comprises a tie plate having an opening on one side of the rail seat and a spring lock disposed in the opening. The lock is generally C-shaped with its upper arm engaging the top 10 of the rail base, the lower arm being disposed under and engaging the bottom surface of the plate. A retainer is driven into the plate opening between the outer face of the lock and the outer wall of the opening and acts to wedge the lock 15 firmly against the inner wall of the opening so that the upper arm of the lock exerts a thrust of a predetermined magnitude on the top of the rail base.

In the preferred construction, the retainer is 20 provided with a tapered shank and a shoulder projecting laterally from the top of the shank and normally engaging the top of a raised abutment extending transversely of the plate adjacent the rail seat, the abutment being wide 25 enough to accommodate the opening for receiving the lock and to provide a raised surface outwardly of the opening against which the shoulder of the retainer is driven. The retainer may be provided above the shoulder with a head by 30 which the retainer may be held to position its shank in the plate opening, the head providing 35 a suitable striking surface for use in driving the retainer into position.

The retainer shank preferably tapers downwardly and slightly outwardly from the shoulder 40 to a point in the mid-section of the shank, and then inwardly and downwardly to the lower end of the shank. The lower inwardly tapered portion of the retainer shank thus forms a wedge 45 by which the retainer may be forced down between the spring lock and the outer wall of the opening in the tie plate, and the upper outwardly tapered portion of the shank forms an inverted wedge which, due to the spring action of the lock, securely holds the retainer in position.

The spring lock may be installed readily by simply inserting it in the plate opening with its upper arm in engagement with the rail base and striking the upper portion of the lock with a hammer or the like so that the lower arm is

driven down below the surface of the tie, which may have a recess previously formed therein for receiving the lock. By reason of the form of the lower part of the lock and the fulcrum action of the upper arm on the rail base, the lower arm of the lock thus is driven downwardly and inwardly under the tie plate, until the lower part of the lock engages the bottom surface of the plate. At this time the upper part of the lock is held away from the inner wall of the opening by engagement of the upper arm of the lock with the top of the rail base. The lower tapered end of the retainer is then inserted between the outer face of the lock and the outer wall of the plate opening and is driven downwardly until the retainer shoulder engages the top of the raised abutment on the plate. In the downward movement of the retainer, the tapered portion of the shank acts as a wedge and forces the upper part of the spring lock inwardly toward the rail about the lower part of the lock as a pivot. Thus the lock pivots first on its upper arm in driving the lower arm into the tie under the plate, and then on its lower arm when the lock is wedged inwardly by the retainer.

When the retainer has been driven down to the limit set by the shoulder, the spring action of the lock tilts the upper portion of the retainer shank outwardly so that it is flat against the outer wall of the opening in the plate. With the retainer in this position, the outward and downward taper of the upper portion of its shank forms an inverted wedge securely holding the retainer against accidental withdrawal and against gradually being worked loose. Also the spring lock, by reason of its reactive force against the retainer, automatically takes up any looseness which might otherwise develop in the parts. The spring lock is of sturdy construction and lies close to the rail flange so that it is not likely to be damaged by dragging equipment, thus affording an added feature of safety. The spring lock and the plate opening for receiving it may be easily formed, and the opening is adapted to accommodate either the lock and retainer or a spike or other hold-down means, so that the parts are interchangeable.

For a better understanding of the invention reference may be had to the accompanying drawing, in which

Fig. 1 is a longitudinal sectional view of one form of the new fastening;

Fig. 2 is a plan view of the fastening shown in Fig. 1 and,

Fig. 3 is a longitudinal sectional view of part of the fastening shown in Figs. 1 and 2, illustrating the position of the parts when the retainer is first inserted in the opening.

The new rail fastening, as shown, comprises a tie plate 10 seated on a tie 11 and having a canted rail seat 12 for supporting the rail 13. Extending transversely of the tie plate on each side of the rail seat is a rail abutment shoulder 14. Preferably, each shoulder is formed by an upwardly projecting portion on the plate extending outwardly a substantial distance from adjacent the rail base, so as to provide a generally horizontal raised surface which terminates in a downwardly inclined surface 14a. The raised portion 14-14a may be formed on the top of the plate in a rolling operation.

At each side of the rail seat, the tie plate is provided with a substantially square opening 16 extending completely through the plate from the top of the raised portions 14-14a. The rail is

held yieldingly on its seat by a spring lock 17 which, as shown, comprises a section of relatively heavy spring metal, the lock being preferably of rectangular section and having an upper rail engaging arm 18 and a generally vertical shank portion 19 which is integrally connected to the arm 18 by a reinforced throat 18a. The lock is disposed in the opening 16 and is provided at its lower portion with an inwardly extending arm 20 generally parallel to the arm 18 but substantially shorter, the arm 20 lying in a recess 20a in the tie under the plate and extending under part of the plate adjacent the inner wall of the opening, whereby the plate prevents upward movement of the lock in the opening.

The spring lock is held in position in the opening by a retainer 22 comprising a shank 23 wedged into the opening between the outer wall of the lock and the outer wall of the plate opening, the wedging action of the retainer serving to hold the vertical portion 19 of the lock against the inner wall of the opening. The upper outer surface 23a of the shank tapers slightly outwardly and downwardly so that the shank portion diverges gradually from the shoulder to a protruding point 23b, and the lower outer surface 23c tapers downwardly and inwardly relatively sharply to the end of the shank. Preferably, the inner face 22a of the retainer is flat and contacts the outer curved surface of the lock approximately in the line of thrust of the rail flange above the level of the protrusion 23b and below the top of the rail abutment shoulder 14. Above its shank portion 23, the retainer is provided with an outwardly extending shoulder 24 engaging the top of the raised shoulder 14 of the plate outwardly of the opening, and above the shoulder the retainer has a striking head 25.

In the installation of the new fastening, the lock 17 is inserted in the opening 16 in the position shown in dotted lines in Fig. 1, with the lower arm 20 of the lock engaging the inner wall of the plate opening. In this initial position of the lock, its outer surface engages the outer portion of the raised abutment 14 and the arm 18 engages the top of the rail base. The upper surface of the lock above the opening is then subjected to a series of angular blows which cause the lock to fulcrum on its rail engaging end 18 as a pivot while the lower end portion 20 is forced under the tie plate. The lower end of the arm 20 may be sufficiently sharp to penetrate the tie and move inwardly beneath the plate under the impact of the blows, but advantageously, the recess or depression 20a under the plate opening 16 is preformed to facilitate the application of the spring lock. After thus initially introducing the lock into engagement with the plate bottom and the top of the rail base, the lower tapered end of the retainer 22 is inserted in the space between the lock and the outer wall of the plate opening. The head 25 of the retainer is then subjected to a sharp blow or series of blows which forces the retainer downwardly in the opening until its shoulder 24 engages the top of the raised plate shoulder 14. The retainer in its downward movement acts as a wedge and causes the lock to pivot on the lower inner edge of the plate opening 16, the upper arm 18 of the lock being urged inwardly and upwardly on the rail base to the position shown in full lines in Fig. 1. In the final position of the parts, the edge of the rail base may be engaged by the reinforced throat portion 18a of the lock.

It will be apparent that in the installation of

the fastening, the lock 17 cannot be overdriven because the inner wall of the plate opening limits the inward movement of the lock, and the retainer 22 cannot be overdriven due to engagement of the shoulder 24 with the raised plate portion 14—14a. The distortion of the spring lock and the resulting spring action transmitted to the rail and plate are directly proportional to the change of the angular relation between the lock arms 18 and 20, the degree of which may be predetermined and controlled by the form and physical properties of the lock itself. The sturdiness of the lock and the locking action of the retainer 22 provide a high factor of safety against torque or other stresses developed in the lock incident to its resistance to movements of the rail and to the action of high speed traffic.

Because of the wedging action of the retainer 22 and the angular relation of the lock arms 18 and 20 to the shank portion 19 of the lock, the driving of the retainer causes the lock arm 18 to move upwardly on the rail flange so that a downward pressure is developed against the top of the rail base and the arms of the lock are forced apart to distort the lock. The distortion of the lock produces a reactive force in the form of an outward thrust against the retainer 22 above the level of the protrusion 23b. Consequently the upper portion of the retainer shank is tilted outwardly on the protrusion as a pivot so as to lie flat against the outer wall of the opening 16. As the surface 23a of the retainer shank tapers outwardly and downwardly with respect to the lock engaging surface 22a, it forms an inverted wedge between the lock and the plate which positively secures the retainer in the plate opening. Thus the retainer is prevented from working loose or becoming accidentally withdrawn as a result of vibration or other cause.

The spring action developed on the rail base and the tie plate through the lock arms 18 and 20 serves to retard the vertical movement of the rail incident to passing wheel loads and also dampens vibration and opposes lateral and longitudinal movement of the rail on the plate due to traffic conditions or thermal changes in the rail itself. Because of the lateral reactive force of the lock on the retainer, any looseness which might otherwise develop between the parts in the plate opening and the walls of the opening due to wear, corrosion, etc., is automatically taken up by movement of the lock in a clockwise direction on the lower inner edge of the plate opening as a pivot.

Since the lower arm 20 of the lock is driven under the bottom surface of the tie plate, it is unnecessary to provide a special form of plate opening having an undercut portion for receiving the arm. Accordingly, the opening 16 may be made substantially square throughout its length so that it will accommodate either the fastening parts 17—22 or the usual spike for holding the tie plate to the tie. The plate may be held to the tie by the use of conventional bolts,

lag screws, screw spikes, or the like. However, we prefer to secure the plate to the tie by the use of a form of spike 31 having its front and back sides parallel and its lateral sides tapered from the head downwardly to the normal cross section of the spike, the length of the tapered portion being substantially equal to the depth of the plate opening, and the taper being of a degree to provide a wedged bearing with the sides of the plate opening so that these sides prevent driving of the spike head against the top of the rail base. This construction insures retention of the spike head in spaced relation to the rail base, as shown at the left in Fig. 1. If desired, additional spike openings 32 may be provided in the tie plate outwardly of the raised abutments 14—14a, and these openings are preferably proportioned so that they exert a wedging action on the tapered sides of the spike shank, as described in connection with the spike 31.

We claim:

In a rail fastening assembly, the improvement comprising a tie-plate seated on a tie, a recessed rail-seat in the top of the tie-plate, a rail supported in the recess, a plate-opening immediately adjacent the rail seat, a raised abutment shoulder on the tie-plate forming a walled backing around three sides of the plate-opening above the level of the recessed seat, said walled backing being adapted to resist reactive forces transmitted laterally through securing means in the opening by movement of the rail when a wheel load is moved thereon, a spring-lock in the plate-opening having one end disposed under and engaging the bottom of the tie-plate and the other end engaging the top of the rail base with a spring action, said spring-lock being generally C-shaped and lying close to the rail flange so that it is not likely to be damaged by dragging equipment, a retainer driven into the opening between the spring-lock and the outer wall of the opening, said retainer being provided with a laterally extending shoulder and a shank below the shoulder wedged into the opening and the wedging action of the retainer serving to hold the vertical portion of the spring-lock in the opening against the inner wall of the opening, the upper outer surface of the shank tapering slightly outwardly and downwardly so that the shank portion diverges gradually from the shoulder to a protruding point, and the lower outer surface of the shank tapering downwardly and inwardly relatively sharply to the end of the shank, said vertical portion of the spring-lock in the opening having its engaging surface contiguous to the retainer tapering inwardly and downwardly so that the retainer forms an inverted wedge between the spring-lock and the tie-plate, the laterally extending shoulder engaging the top of the raised abutment shoulder of the tie-plate adjacent the opening and the retainer being provided with a striking head above the laterally extending shoulder.
